DESIGN FOR A LIGHTING FIXTURE

Carl Friedrich Woerner and Thaddeus A. Walsh,
Chicago, Ill.

Application December 16, 1939, Serial No. 88,936

Term of patent 7 years

To all whom it may concern:

Be it known that we, Carl F. Woerner and Thaddeus A. Walsh, citizens of the United States, residing at Chicago, in the county of Cook and State of Illinois, have invented a new, original, and ornamental Design for Lighting Fixtures, of which the following is a specification, reference being had to the accompanying drawing, forming a part thereof.

Fig. 1 is a side elevation in perspective of a lighting fixture, embodying our new design;

Fig. 2 is a section taken upon the line 2—2 in Fig. 1.

We claim:

The ornamental design for a lighting fixture, as shown.

CARL FRIEDRICH WOERNER.
